UNITED STATES PATENT OFFICE

91,861

DESIGN FOR A DOOR HANDLE FOR CABINETS OR THE LIKE

Leonard H. Darbyshire, Detroit, Mich., assignor
to Norge Corporation, a corporation of Michigan

Application October 25, 1933, Serial No. 49,545

Term of patent 14 years

To all whom it may concern:

Be it known that I, LEONARD H. DARBYSHIRE, a citizen of the United States and a resident of Detroit, in the county of Wayne and State of Michigan, have invented a new, original, and ornamental Design for a Door Handle for Cabinets or the like, of which the following is a specification, reference being had to the accompanying drawing, constituting a part hereof, and in which:

Fig. 1 is a side elevational view of a door handle for cabinets or the like and embodying my new and ornamental design;

Fig. 2 is a front elevational view of a door handle embodying my design;

Fig. 3 is a top plan view of the door handle illustrated in Figs. 1 and 2; and

Fig. 4 is a plan view of the door handle em-

bodying my design and looking upwardly from the bottom thereof.

My door handle is characterized by the provision of a design embodying a plurality of symmetrically disposed outstanding elongated portions gradually tapering from a relatively wide off-center portion to the rounded ends of said portions and providing an escutcheon plate portion and a hand grasp portion affording a means for actuating a door lock-releasing mechanism.

I claim:

The ornamental design for a door handle for cabinets or the like substantially as shown and described.

In testimony whereof, I have hereunto subscribed my name this 21st day of October, 1933.

LEONARD H. DARBYSHIRE.
